UNITED STATES PATENT OFFICE.

ANDREW PREUSS AND FREDERICK JANSSON, OF CHICAGO, ILLINOIS.

MECHANICAL FOOT-CLEANER OR DOOR-MAT.

SPECIFICATION forming part of Letters Patent No. 732,373, dated June 30, 1903.

Application filed November 6, 1902. Serial No. 130,234. (No model.)

To all whom it may concern:

Be it known that we, ANDREW PREUSS and FREDERICK JANSSON, citizens of the United States, residing at Chicago, in the county of Cook and State of Illinois, have invented a new and useful Mechanical Foot-Cleaner or Door-Mat, of which the following is a specification.

Our invention consists of a mechanical foot-cleaner or door-mat having brushes which are automatically operated to clean the feet as a person walks across the mat.

Our primary object is to provide a mechanical foot-cleaner of simple and inexpensive construction capable of performing efficiently the work mentioned.

Our invention is illustrated in the accompanying drawings, in which—

Figure 1 is a plan view of our improved door-mat having automatic brushes; Fig. 2, a longitudinal section taken as indicated at line 2 of Fig. 1; Fig. 3, a view in side elevation, and Fig. 4 a cross-sectional view taken as indicated at line 4 of Fig. 1.

In the form shown the device comprises a rectangular frame A, having vertical sides and ends forming a low casing provided with inner corner members a, attached to the sides and having their upper outer portions cut away to afford slots a' and shoulders a'; a yieldingly-supported open-work frame or foot-plate B, having end members b moving in the slots a' and longitudinal slats or bars b' connecting said end members; a series of shafts C, journaled in bearings C', with which the side members of the frame A are provided; pinions C² on said shafts; brushes C³ on said shafts and located within and beneath the spaces between the bars b'; gear-segments D, meshing with the pinions C² and supported upon pivots D', projecting inwardly from the side members of the frame A; links D², connected at their upper ends by pivotal screws d with the two outer slats b' and connected at their lower ends by pivotal screws d' with the short arms d² of the gear-segments D; cross-bars E, supported on the shoulders a', and springs E', supported by the bars E and bearing the frame B.

As shown in Figs. 1 and 2, the inner end margins of the members b of the frame B bear against the inner walls of the slots a', so that longitudinal play of the frame B is prevented.

The members b are equipped at their extremities with wheels f, which engage the inner surfaces of the side members of the frame A to prevent undesirable lateral play of the frame B. We have shown one lateral margin of the mechanical foot-cleaner equipped with a covering plate or board g, which conceals the pinions and gear-segments located beneath it. The opposite side of the device may be similarly provided, if desired. As shown, however, this plate is omitted at one side and the upper central portion of said side is cut away at h to facilitate stepping upon the mat, the particular purpose being to prevent the heels from being caught by the side plate as the frame B is depressed under the weight of the person stepping upon the mat. In the construction shown we have omitted the pinions and gear-segments from the ends of the two intermediate shafts C adjacent to the cut-away point h.

In use the mat is placed before a door, with the cut-away side out, and a person walking across the same, preferably transversely of the slats b', will cause the frame B to be depressed, thereby swinging the gear-sectors D and rotating the brushes. The weight of the person crossing the mat depresses the frame B beneath the level of the upper portions of the brushes, and the rotating brushes operate to clean the person's shoes. As the weight upon the frame B is momentarily relieved as the foot is being raised, the frame is restored or partially restored to its normal position, thereby reversing the direction of movement of the brushes.

Each of the slats of the yielding grate or foot-plate is provided with a series of downward projections k, which aid in keeping the brush-sections in their proper spaces, thereby preventing them from becoming injured. The brushes are of any suitable material and are formed independently of the square shafts upon which they are fixed. It will be observed that when either lateral edge of the foot-plate is depressed at least two of the brush-shafts are caused to rotate, thereby drawing the other lateral edge downwardly, so that the foot-plate settles down in a practically parallel movement.

It will be understood that various changes in details of construction within the spirit of

our invention may be made. Hence no undue limitation is to be understood from the foregoing detailed description, which has been given for clearness of understanding only.

5. What we regard as new, and desire to secure by Letters Patent, is—

1. In a device of the character described, the combination of a stationary frame, movable cleaning devices supported thereon, a 10 yieldingly-supported open-work foot-plate located above said cleaning devices, and actuating means for said cleaning devices connected with said foot-plate, for the purpose set forth.

15. 2. In a device of the character described, the combination of a stationary frame, rotary brushes supported thereon, a yieldingly-supported foot-plate above said brushes, and means connected with and moved by said 20 foot-plate for actuating said brushes, for the purpose set forth.

3. In a device of the character described, the combination of a stationary frame, rotary brushes supported thereon and equipped with 25 pinions, a movable open-work foot-plate above said brushes, springs supporting said foot-plate, gear-segments pivotally supported on said frame and meshing with said pinions, and links connecting said gear-segments with 30 said foot-plate, for the purpose set forth.

4. In a device of the character described, the combination of a stationary frame, rotary brushes journaled in said frame a distance 35 below the upper surface thereof, a spring-supported open-work foot-plate within said frame above said brushes, and actuating means for

said brushes connected with said foot-plate, for the purpose set forth.

5. In a device of the character described, the combination of a stationary frame, a 40 spring-supported foot-plate comprising suitably-connected slats separated by spaces, shafts equipped with brushes located within and beneath the spaces between said slats, and brush-operating means connected with 45 said foot-plate, for the purpose set forth.

6. In a device of the character described, the combination of a stationary frame, a plurality of transversely-extending rotary brushes journaled thereon and equipped with 50 pinions, one of said brushes, at least, having pinions at both ends, a yieldingly-supported open-work foot-plate, and gear-sectors pivoted on said frame and meshing with said pinions and connected with said foot-plate, 55 for the purpose set forth.

7. In a device of the character described, the combination of a rectangular stationary frame, rotary brushes journaled in said frame beneath the upper surface thereof, a yieldingly-supported open-work foot-plate, and actuating means for the brushes, one side of said frame having a portion terminating below said foot-plate, whereby the foot is prevented from striking against the frame when 60 the foot-plate is depressed, for the purpose set forth.

ANDREW PREUSS.
FRED. JANSSON.
